UNITED STATES PATENT OFFICE.

THOMAS GREEN, OF WASHINGTON, DISTRICT OF COLUMBIA.

GAME APPARATUS.

Application filed April 17, 1924. Serial No. 707,215.

To all whom it may concern:

Be it known that I, THOMAS GREEN, a citizen of the United States, residing at Washington, in the District of Columbia,

5 have invented a new and useful Improvement in Game Apparatus, of which the following is a specification, reference being had to the accompanying drawing.

My invention relates particularly to apparatus adapted to be used for playing a game in imitation of a real football game played in the usual manner on a football field.

The object of the invention is to produce such an apparatus suited to the playing of 15 such an imitation game on lines closely related to the performances in actual football games played by leading football teams.

In my improved apparatus provision is made for conducting the imitation game 20 with reference to the average of results of various plays in actual games between leading football teams.

In the accompanying drawings

Fig. 1 is a plan of a structure bearing a 25 diagram of the football field now in general use for the playing of actual football games;

Fig. 2 is an end elevation of the structure shown by Fig. 1;

Fig. 3 is a plan of a circular disc adapted 30 to bear a diagram indicating various plays, also a pointer adapted to be brought into relation with symbols and legends on the diagram;

Fig. 4 is an elevation of the structure 35 shown by Fig. 3, a part being broken away;

Fig. 5 is a detail of the pointer clamp detached from the supporting bar;

Fig. 6 is an upright section on the line, 40 6-6, of Figs. 3 and 4, looking in the direction of the arrow;

Fig. 7 is a diagram to be placed on the disc of Fig. 3;

Fig. 8 is a schedule of symbol abbreviations.

45 In the diagram of Fig. 1, A, A are the side lines. B, B are the goal lines. C, C are the end lines. D, D are the 20 yard lines which connect the side lines, A, A. E, E are minor lines which are parallel to the major cross lines and are spaced 5 yards from each other. These transverse lines are numbered serially from each goal line, G, to the other goal line, the intervals being in fives, and the middle transverse line bearing 50 the number, 50. On each goal line is the goal, G.

The imitation game to be played with my apparatus treats this field in all respects as the football field is treated in actual playing of football.

60 This diagram is placed on any suitable base, F, adapted for the insertion of pins or other markers along the side lines in holes 1 yard apart to indicate the positions at the time of the ball.

65 Referring now to Figs. 2, 3 and 4, H is a base, preferably horizontal. H¹ is a disc placed parallel to the base, H, and mounted for rotation on the axis of the disc. H² is an axle extending through the disc on the axial line of the disc. The lower end of said axle is conical and rests in a bearing, H³. The upper end of said axle is conical and rests in a bearing formed in the lower end of a bearing screw, H⁴, threaded into the supporting bar, H⁵, which extends across the disc and has feet, H⁶, secured to the base, H. Thus the disc is held for easy rotation in the bearings, H³ and H⁴. On the periphery 70 of the disc are lugs or tongues, H⁷, adapted to be engaged by the hand of either player for spinning the disc on its axis.

75 On the supporting bar, H⁵, is an adjustable pointer, I, which extends downward nearly to the upper face of the disc, H¹. Said pointer is supported rigidly on a clamp comprising horizontal jaws, I¹, and a blade spring, I². One of said jaws bears against the lower face of the supporting bar. The other of said jaws extends across the upper 80 face of the supporting bar and is high enough above said bar to allow the insertion of the blade spring, I², the blade spring being curved upward between its ends and bearing against the lower face of the upper jaw and having its ends bearing against the upper face of the supporting bar. By this means, the pointer structure is held frictionally on the supporting bar and may be moved by either player toward and from 85 the disc axle, H².

90 On the disc are circles, J, concentric to the disc axis and spaced approximately even. Between these circles are ring-form zones, J¹, each relating to a different play.

95 The inner and the outer circular lines, J, are joined by radial lines, J², which are spaced from each other approximately evenly, whereby the ring-form zones, J¹, are divided into approximately rectangular sections or fields adapted to receive symbols or indicia relating to the game. On each sec- 100

140

tion between two adjacent radial lines, J^2 , is indicated, by words, or symbols a course or step which may be undertaken by the side in possession of the ball. Thus all the sections of each zone relate to the step thus noted in one of the sections of that zone. Thus the inner or first zone relates to "Run back of kick-off," and the second zone relates to "Punt, field goal attempt and kick-off" and the third zone relates to "Forward pass," and the fourth or outer zone relates to "Pass run," after "Completed or intercepted Forward pass" and "Run back of punts and field goal attempts," and also to "Running plays."

All sections but one of the first zone bear numbers indicating values. In the second zone all the sections, excepting one, bear numbers and two have both numbers and symbols indicating values or situations. Those three bear words or numbers relating to punting and field goal attempting and kick off.

In the third zone, all the sections other than the section "Intercepted line of scrimmage", contain two numbers indicating or expressing values, the two numbers in each section being divided by a diagonal line. On each of these sections, the larger number is even and the smaller number is one-half of the larger number. The larger numbers are made even, in order that one-half thereof will be a whole number and not a fraction, as described further on.

In the fourth or outer zone, five of the sections bear the words, "No gain". The other sections, excepting three, of that zone, bear two different numbers, separated by diagonal lines, as above described regarding the third zone. In one of those three sections appears "Minus 5P". In another of said sections appears "Plus 5P". In another appears "Fumble".

The values for this game are taken from the actual performances of such representative teams as the United States Naval Academy, United States Military Academy, Yale, Harvard, Princeton, etc. It is balanced in all departments. Therefore it produces excellent modern football. Both sides take the field with the same possibilities. Hence a premium is placed upon careful attack.

In playing my game, the National Collegiate Athletic Association football rules apply, except as to some details.

The players agree upon time of halves. No change of goals is made at quarter time, or at the beginning of the second half as no advantage would accrue to either side. After time of halves has been agreed to, toss coin, winning side has option of kicking off or receiving the kick off from opponent. The side which does not get this option at the beginning of the game, does

get it at the beginning of the second half.

The side which is to kick off moves the pointer into the appropriate zone (in this case the second) and puts the ball on the 50 yard line and spins the dial and reads the kick off value indicated in the second zone by the section under the pointer when the disc stops. The ball is then moved in the direction of the receiving side's goal as far as the distance given by the dial reading. The side receiving now spins the dial for run back of kick off as shown in the first or inner zone. After this has been done and the ball moved accordingly, the receiving side starts "First down 10 yards to go". Now the offensive side must advance the ball 10 yards or more in four or a less number of attempts to retain the ball. As soon as the required distance of 10 yards or more is made, even if on less than four attempts, a new "First down 10 yards to go" is started and no credit is carried over. The attempts may take the form of "Running play", "Forward pass", "Punt" or "Field goal attempt". The form chosen must be announced by the player before the spin is made. The result in each case is ascertained by a dial reading given in the appropriate zone.

Drop kicks (also place kicks) summed up in the general term, "Field goals," are made as indicated in the following table: (they fall short or result in touchbacks as shown by punt values in second zone on dial).

Field goal table.

Ball passed back by center from—	Field goal made by, following values in second zone and counts 3 points.	100
Inside of defensive 20 yd. line—		
20 to 25 yd. lines (both incl.)—	Punt value 20, 25, or 30.	
25 to 30 yd. lines (both incl.)—	Punt value 20 or 25.	
30 to 35 yd. lines (both incl.)—	Punt value 30 only.	
35 to 40 yd. lines (both incl.)—	Punt value 35 only.	
40 to 45 yd. lines (both incl.)—	Punt value 40 only.	
45 to 50 yd. lines (both incl.)—	Punt value 45 only.	
		105
Inside of defensive 20 yd. line—		
20 to 25 yd. lines (both incl.)—	Punt value 20, 25, or 30.	
25 to 30 yd. lines (both incl.)—	Punt value 20 or 25.	
30 to 35 yd. lines (both incl.)—	Punt value 30 only.	
35 to 40 yd. lines (both incl.)—	Punt value 35 only.	
40 to 45 yd. lines (both incl.)—	Punt value 40 only.	
45 to 50 yd. lines (both incl.)—	Punt value 45 only.	
		110

If offensive side fails at any time to make the necessary 10 yards in four attempts, the ball changes hands after gain or loss if any on fourth attempt has been applied. The defensive side then becomes offensive and starts "First down 10 to go."

When "Fumble of run," (fourth zone) "Run back of kick off," (first zone) "Run back of punt or field goal attempt," (fourth zone) occurs, the decision as to which side gets the ball is made in the fourth zone. Spin the dial and note the reading on the section which stops under the pointer. If one of the sections bearing "No gain" stops under the pointer, there is no gain, and the side which had the ball before the fumble retains it. If any section bearing a minus number, except minus 5P which with plus 5P is not allowed to make decisions, stops

under the pointer, the side which had the ball retains it and moves it back according to the number in that section. The distance through which the ball is to be moved backward depends upon the position of the ball on the field. If the ball is not within the defensive 20 yard line in possession of the offensive side, the ball is moved back according to the larger figure. For instance, if the section contains the number minus 6 and minus 3, the ball is moved back 6 yards. But, if during such play the ball is within the defensive 20 yard line in possession of the offensive side, then the ball is to be moved back according to the smaller number in the section which stops under the pointer. In other words, if the ball is within the defensive 20 yard line in possession of the offensive side, the value is to be reduced. For the sake of convenient reduction and, with that in view, avoiding fractions, I have arbitrarily chosen larger numbers which are even, and which can be divided by two to make an entire and not a fractional number.

If any plus section, including the one bearing "Plus 2 plus 1," which gives the ball to the side which had it when fumble was made stops under the pointer, the ball is to be advanced instead of carried back, but the ball goes to the side which did not make the fumble if "Plus 4 plus 2" section or larger section comes up. In other words, the ball changes side or remains with the same side according to section values. The distance through which the ball is advanced depends upon the position on the field. If the ball is on the defensive 20 yard line or a greater distance from the defensive goal line and the decision is in favor of the defensive side, then the ball is moved the number of yards corresponding to the larger number in the sector. But if the ball is on the defensive 19 yard line or at a less distance from the defensive goal line, then the smaller of the two numbers is used for advancing or reversing the ball, if the decision is in favor of the side attacking that goal.

When blocked punt or blocked field goal attempt appears under the pointer, second zone, the decision is made in a similar manner in the fourth zone, except that the kicking side must get "No gain" or less to retain ball.

After all decisions on fumbles and blocks, the side which receives the ball starts "First down 10 to go."

A touchdown scores six points for the offensive side and is made by offensive side forcing the ball by running play (fourth zone) or forward pass (third zone) on or over the defensive goal line in possession of the offensive side. Scoring a touchdown allows the successful side a try for an additional point. The rules for the game on the

field provide that the ball be placed at not less than three yards from the goal of the side scored upon and a scoring play must be made by the side which made the touchdown. This scoring play must be made in one attempt to get the additional point. The attempt is almost invariably made by the "Field goal" method as the chance of success is much greater. This holds for my game. So for try for point after touchdown please refer to the first line of the above "Field goal table." However the attempt for point after touchdown may be made by "Running play" or "Forward pass" as on the actual field of play.

A field goal (except after touchdown as mentioned above) is made by either a drop kick or place kick, and scores three points for the offensive side. It is made, blocked, falls short, or goes over defensive goal line for touchback from various distances as indicated in the "Field goal table" and by punt values in the second zone of the dial.

After score is made by either a touchdown (with or without additional point) or by field goal, the side scored upon has the option of kicking off to or receiving the kick-off from the opponent and the game is immediately resumed.

A safety scores two points for the side not in possession of the ball at the time. It consists in the side having the ball being thrown back on or behind its own goal line with the ball in its own possession. It scores against the side thrown back. The side scored upon puts the ball on its own thirty yard line and starts offensive "First down 10 to go". A safety may occur by a fumble "Running play" and recovery, by a loss on a "Running play" or run back of punt or field goal attempt which falls short of the goal line or by a blocked "Punt" and recovery, any one of which throws the side with the ball on or behind its own goal line.

A touchback is not a scoring occurrence. It consists in offensive side punting, drop (or place) kicking, (second zone) or forward passing (incomplete) (third zone) on or behind the defensive goal line. In case of touchback, the side which was defensive at the time, becomes offensive, places the ball on its own twenty yard line and starts "First down 10 to go".

The following rules for the forward pass apply to this game when offensive is near defensive goal line. They simulate very closely the happenings on the actual field of play. A forward pass which comes up complete on the defensive goal line, in the defensive end zone, or on the defensive end line is a touchdown for the offensive side. A forward pass coming up incomplete under the same conditions also beyond the defensive end line is a touchback which we have

just described. A forward pass coming up intercepted under the same conditions is considered to have been batted to the ground for an "Incomplete" by the defensive side and results in a touchback. A forward pass which comes up complete beyond the defensive end line is a touch-back. A forward pass coming up intercepted on the defensive one yard line or farther up field from the defensive goal line may be run back by the side which made the interception or it may be considered that the ball was "Batted" to the ground by the defensive side for a loss of a down to the offensive side, just as though the pass were incomplete. If this should happen on fourth down and the defensive side declare what was apparently an "Intercept" to be an "Incomplete", the ball would change hands from where it was put in play. This leaves it to the judgment of the defensive side as to whether the "Intercept" should be taken and run back or the ball declared "Batted" to the ground for an "Incomplete".

25 All complete and intercepted forward passes are handled by two spins of the dial. The first spin is for the pass itself (third zone), and if it comes up complete or intercepted, the second spin (fourth zone) 30 is for the run forward by the offensive in case of complete, or run-back (fourth zone) by the other side in case of interception. Of course no second spin is taken if first spin shows incomplete or brings up a complete which by itself makes a touchdown, or produces a touchback.

Runs for both the run forwards and the run backs of forward passes are indicated in the fourth zone by arrows so that every 40 other "Running play" value is used for this purpose. The values for the pass and pass-run are to be taken as two separate parts of the same down and each must comply with half values in reference to the defensive 45 20 yard line.

It must be carefully borne in mind that the half values apply only to offensive as regards third and fourth dial zones and only when offensive is inside of defensive 20 yard line. 50 The plus $5p$ and the minus $5p$ are never affected by half values and are not allowed to make decisions. Values for run back of punts or run back of attempts at field goal, which in either case fall short of the goal 55 line, i. e., on one yard line or at a greater distance up field from the goal line, are obtained from all sections in the fourth zone. They are subject to fumble and decision as on a play. A fair catch may be called for 60 on reception of any such punt or attempt at field goal. The result of a fair catch is obtained in this way: Spin and if value other than fumble comes up in the fourth zone, the ball is not moved in accordance with the 65 value. However if sector marked "Fumble"

in fourth zones comes up it is decided as a fumbled play would be decided. After a fair catch or a decided fumble of same, "First down 10 to go" comes up for the successful side.

70 The 5 yard penalties have full value in all parts of the field, except that in no case are they allowed to put the ball on or behind the goal lines. In this game, as on the field, a penalty which should apparently put the ball on or behind a goal line is arbitrarily cut down in value to put the ball on the one yard line. In the game on the field, further penalties are applied by having the distance 75 to the goal line. In every case of penalty 80 against the offensive (except in running back a punt or running back attempt at field goal which fell short) the offensive starts after the penalty with the same numbered down 85 as before the application of the penalty but with the added distance of the penalty to go. All penalties in favor of the offensive, bring up "First down 10 to go" for the offensive 90 after the penalty has been applied, in its favor.

95 All penalties of greater value than five yards each have been arbitrarily removed from this game as all heavier penalties are more or less an unsportsmanlike reflection on the side against which they are applied on the field. They mar the game on the field, and would do the same thing if allowed in this game. It is fair and proper that the heavier penalties be removed from this game and allow it to play only clean football. 100 Five yard penalties are almost always the result of eagerness on the field and cast no reflection.

105 In case of an off side kick-off (second zone) another attempt is made but with the ball on kicker's forty-five yard line instead of the fifty yard line. If another off side kick-off comes up, the ball shall go to the receiving side which shall put it on its own forty yard line and start "First down 10 110 to go".

115 A fumbled run back of kick-off is decided like a fumbled running play, (fourth zone) reference being made to the twenty yard line as to the value (that is whole or half value) to be applied.

At any time the dial stops on a line read the next section in a clockwise direction.

120 A practice of short duration will make all of the foregoing plain and easy to remember and will not prove to be complicated even for one not at all versed in the game of football as played on the field.

125 The material necessary to play the game are the dial and values as given, a drawing of a regulation gridiron with the five yard lines marked out and with holes between the five yard lines to indicate one yard spaces (fractions never come up) and two sticks to mark the place where the offensive starts 130

from and the distance to be made to produce first down. One of these sticks has a cube on it, the four sides (omitting the top and bottom sides through which the stick goes) are numbered 1, 2, 3 and 4 and the number of the down coming up is turned toward the field by the defensive side for the information of the offensive side. It also marks the actual position of the ball. Two pins may be also used in lieu of the sticks.

In playing this game, some few situations such as kick off, run back of kick-off, etc., of course leave no option as to what must be done but nearly all of the situations allow choice to the offensive as to the method of attack and give a control of the game practically like that of the quarterback on the actual field of play.

Special rules may be made by the players such as playing until one side scores without regard to time and calling it a game, or playing until one side gets ten or more points, etc. It may be played by several on a side, the majority to decide the method of attack and the captain or quarterback to break all ties if the side has an even number of players. Also it may be played solitaire with interest. It may be played by those with a knowledge of football as played on the field, or it will help those without any such knowledge to a greater appreciation of the game on the field. It can also be played with pleasure as a game entirely in itself without reference to any other game.

35. I claim as my invention,

1. In a game apparatus of the kind described, a representation of a football field, a base having a bearing, a supporting bar supported on and extending across said base and having a bearing, a rotary disc, an axle supporting said disc and seated in said bearings, a pointer supported on said supporting bar, and indicia on the disc expressing football game values, substantially as described.

2. In a game apparatus of the kind described, a representation of a football field, a base having a bearing, a supporting bar supported on and extending across said base and having a bearing, a rotary disc, an axle supporting said disc and seated in said bearings, a pointer shiftably supported on said supporting bar, and indicia on the disc expressing football game values, substantially as described.

3. In a game apparatus of the kind described, a representation of a football field, a base having a bearing, a supporting bar supported on and extending across said base and having a bearing, a rotary disc, an axle supporting said disc and seated in said bearings, a pointer frictionally supported on said supporting bar, and indicia on the disc expressing football game values, substantially as described.

4. In a game apparatus of the kind described, a representation of a football field, a base having a bearing, a supporting bar supported on and extending across said base and having a bearing, a rotary disc having an irregular edge, an axle supporting said disc and seated in said bearings, a pointer supported on said supporting bar, and indicia on the disc expressing football game values, substantially as described. 75

5. In a game apparatus of the kind described, a representation of a football field, a base having a bearing, a supporting bar supported on and extending across said base and having a bearing, a rotary disc having projections on its edge, an axle supporting said disc and seated on said bearings, a pointer supported on said supporting bar, and indicia on the disc expressing football values, substantially as described. 80

6. In a game apparatus of the kind described, a representation of a football field, a base having a bearing, a supporting bar supported on and extending across said base, a screw bearing in said supporting bar, a rotary disc, an axle supporting said disc and seated in said bearings, a pointer supported on said supporting bar, and indicia on the disc expressing football game values, substantially as described. 85

7. In a game apparatus of the kind described, a representation of a football field, a base having a bearing, a supporting bar supported on and extending across said base and having a bearing, a rotary disc, an axle supporting said disc and seated in said bearings, a pointer structure supported on said bar and comprising a pointer and jaws and a spring, and indicia on the disc expressing football game values, substantially as described. 90

8. In a game apparatus of the kind described, a representation of a football field, a base, a disc supported on said base for rotation, indicia on the disc expressing football game values, a pointer structure supported by said base and extending over said disc, and a pointer shiftable on said structure relative to the axis of rotation, substantially as described. 105

9. In a game apparatus of the kind described, a representation of a football field, a circular play diagram and a pointer, said diagram and said pointer being relatively rotatable and the pointer being shiftable relative to the axis of rotation, and said diagram consisting of concentric circles between which are annular sectional play zones bearing indicia identifying the zones and bearing other indicia distributed around the zones and indicating play values or results of play, substantially as described. 115

10. In a game apparatus of the kind described, a representation of a football field, a circular play diagram and a pointer, said

- diagram and said pointer being relatively rotatable and said diagram consisting of concentric circles between which are annular sectional play zones bearing indicia identifying the zones and bearing other indicia distributed around the zones and indicating play values or results of play, the sections of the outer of said zones which bear numerical values each bearing indicia expressing two such values, the two in each section bearing to each other the same ratio as the two in other sections bear to each other, substantially as described.
11. In a game apparatus of the kind described, a representation of a football field, a circular play diagram and a pointer, said diagram and said pointer being relatively rotatable and the pointer being shiftable relative to the axis of rotation, and said diagram consisting of concentric circles between which are annular sectional play zones bearing indicia identifying the zones and bearing other indicia distributed around the zones and indicating play values or results of play, the outer of said zones which bear numerical values each bearing indicia expressing two such values, one of said values being a multiple of the other, substantially as described.
12. In a game apparatus of the kind described, a representation of a football field, a circular play diagram and a pointer, said diagram and said pointer being relatively rotatable and the pointer being shiftable relative to the axis of rotation, and said diagram consisting of concentric circles between which are annular sectional play zones bearing indicia identifying the zones and bearing other indicia distributed around the zones and indicating play values or results of play, the sections of the outer of said zones which bear numerical values each bearing indicia consisting in part of two whole numbers, one of which is a multiple of the other, substantially as described.
13. In a game apparatus of the kind described, a representation of a football field, a circular play diagram and a pointer, said diagram and said pointer being relatively rotatable and the pointer being shiftable relative to the axis of rotation, and said diagram consisting of concentric circles between which are annular sectional play zones bearing indicia identifying a zone for a plurality of purposes and indicating the same values for those purposes, substantially as described.

In testimony whereof I have signed my name, this 16th day of April, in the year one thousand nine hundred and twenty-four.

THOMAS GREEN.
